UNITED STATES PATENT OFFICE.

CHARLES H. CROWELL, OF SWAMPSMOTT, MASSACHUSETTS.

MOISTENING MACHINE.

1,081,582.

Specification of Letters Patent. Patented Dec. 16, 1913.

Application filed December 22, 1911. Serial No. 667,363.

To all whom it may concern:

Be it known that I, CHARLES H. CROWELL, a citizen of the United States, residing at Swampscott, county of Essex, State of Massachusetts, have invented a certain new and useful Improvement in Moistening-Machines, of which the following is a specification, reference being had therein to the accompanying drawings.

10 My present invention relates to moisteners for gummed tape of the type of machines which contain a roll of gummed tape and deliver the same as required to a wetting or moistening roll by means of which the adhesive on the tape is softened, means being provided for severing the tape at the proper point.

One object of the invention is to provide means for drawing the protruding end of the gummed tape back under a plate after the wetted portion has been severed in order that it may be maintained flat and convenient for use.

Another object is to so construct the severing and wetting devices that the protruding end of the tape shall not be wet or moistened and may, therefore be handled thereafter without sticking to the fingers of the user. In machines of this character, so far as known to me, it has heretofore been customary to use a roll of gummed tape, the outside of which is ungummed, and the side next the preceding layer is gummed. My machine also makes it possible and convenient to use tape which is wound with the gummed side outside, but which will be delivered with the ungummed side uppermost.

The invention will be fully understood 40 from the following description taken in connection with the accompanying drawings, and the novel features will be pointed out and clearly defined in the claims at the close of the specification.

45 In the drawings, Figure 1 is a top plan view of a machine embodying my invention. Fig. 2 is a side elevation of the same machine. Fig. 3 shows the retractor in its uppermost position. Fig. 4 is a detail of the 50 construction of the adjustment, provided for the purpose of enabling the machine to be employed with tapes of different widths.

Referring to the drawings, at A is shown a base, to which is secured a hollow cylindrical casing or container B, within which the

roll of gummed tape is received. Said tape is shown at C, in Fig. 2.

At D is shown a moistening roll, the periphery of which dips in a suitable trough E, containing the moistening liquid. Intermediate between the cylindrical casing B and the moistening roll D are located a presser foot F, which bears upon the tape and regulates the tension, a retractor G, a guide H, and a knife or other severing device K.

The cylindrical casing within which the tape is received consists of a circular wall secured at 11 and 12 to the base plate, and two adjustable circular walls or side plates 13, and 14, see Fig. 1. The said cylindrical casing is provided with an opening at 15, through which the tape C is led, being guided over an extension 16 of another portion 17 of said casing B. The roll of gummed tape is free to revolve on an axle 18 carried on two movable uprights 19 and 23, one of which 19 is provided with two pins 20, 20, adapted to engage the holes 21 in the base A. To the upright 19 is secured the side plate 13 and the axle 18. It will therefore be seen that the side plate 13 may be conveniently adjusted lengthwise of the axle by putting the pin 20 in whichever of the holes 21 is most convenient. The other 80 end of the axle 18 passes through the other side plate 14, which is loose thereon, and into a bearing in the upright 23. Said upright is adjustable lengthwise of said axle 18 by means of a thumb nut 25 working in a slot 26 in the bottom of the standard 23. When it is desired to put in place a new roll of the gummed tape, the roll is placed on the axle 18 and the upright 19 and side plate 13 secured thereto are adjusted according to the 95 width of the gummed tape employed, by means of the pins and holes 20 and 21; thereafter the other side plate 14 is put in place, and the standard 23 is slipped over the end of the axle and it is pressed toward the roll of gummed tape, compressing a spring 27 which assists to regulate the tension on the tape and prevent the roll spinning. The upright 23 is thus secured in place by the screw 25.

The gummed tape as it emerges from the cylindrical casing B passes through the opening 15 and under the presser foot F which is provided with a vertical stud 28, passing through a yoke 29 secured at 110

to the sides of the standard or base of the machine. A spring 31 forces the presser foot F down upon the tape with a yielding pressure. After leaving the presser foot 5 the tape passes downward through the retractor which consists, in the form shown in the drawings, of a portion 32 of a cylinder with which co-operates a correspondingly shaped part G, which I have already 10 referred to as the retractor. This retractor G is movable vertically, being guided by two posts 33, 34 on the base of the machine over which fit two tubes 35, 36, secured to the retractor, and the retractor is relatively 15 light and is lifted by the tape when it is pulled out and serves to draw back the end of the tape after the used portion has been severed from it to a point determined by the size of the retractor. This retractor is 20 so constructed and proportioned that it will perform its function without causing the roll of tape in the cylindrical casing B to move. After passing through the retractor, the tape passes under a plate H secured by 25 screws 37 and 38, the object of said plate being to maintain the gummed tape in a substantially flat condition convenient for use without putting unnecessary tension on the tape.

30 While I have described the retractor as semi-cylindrical in form and believe that to be the most satisfactory shape, it is obvious that its essential feature is a moving member which will be moved in one direction by 35 the tape when the tape is drawn out and which will thereafter press upon the tape to draw the end thereof back under the plate or guide H so that it will be kept flat and convenient to handle.

40 After emerging from the end of the plate H, the gummed tape passes over the moistening roll D, but the tape is protected by a doctor 39 from contacting with the surface of the moistening roll before reaching a pre- 45 determined point. The distance from the edge of the feed plate H to the edge of the doctor is about equal to the distance from the edge of the plate to the edge of the knife K so that the gummed tape is severed sub- 50 stantially on the line between the wetted and unwetted portions. The knife acts on the ungummed side of the tape so that there is no tendency to scrape off the gum onto the knife, which would be the case if it acted 55 against the gummed side of the tape. The knife is preferably saw-toothed, as shown in Fig. 1, and is adjustably supported on uprights or standards 40 above the edge of the feed plate H. It will be seen therefore 60 that after the gummed tape has been pulled out and drawn over the moistening roll D it is lifted up by the hand of the operator, and severed on the knife K at a point about 65 on the line between the moistened and un- moistened portions so that the portions C

protruding from the end of the feed plate H is not left in a sticky condition which is unpleasant to handle.

By locating the knife above the moistening roll and at a distance therefrom as described, it will be seen that the operator himself moves the tape away from the moistening roll before the tape is severed, and the doctor prevents the hand of the operator coming in contact with the moistening 70 roll when seizing the end of the strip of tape to pull it out. When the gummed tape is pulled out, the retractor G is lifted up to the position shown in Fig. 3, and it so remains until the stay strip has been severed 80 on the knife K. Thereafter the weight of the retractor G presses down the stay strip into the cup-shaped portion 32 and draws the end of the tape into the space under the guide H, the amount which protrudes de- 85 pending upon the size of the retractor. In practice, the machine is constructed so that about one-half inch of the end of the tape protrudes, this being a convenient amount for the user to seize hold of to pull out the 90 tape when the next piece is required.

The moistening roll D is made of any convenient material as for instance of brass with a thin covering of felt or similar material. A small slit or opening 51 is left 95 near the top of the casing B and transversely thereof in which is located a small lug or projection 52 on the edge of the side plate 13. Adjacent this opening is placed a scale 53 which is graduated with the widths 100 of tape to be employed with the moistener.

The side plate 13 having been adjusted by means of the pins 20 and holes 21 as previously described assumes a positive position, and the roll is held against this side plate 105 by the other side plate and the thumb nut 25 with whatever pressure is deemed advisable. The scale 53 indicates the position of the side plate 13 and hence the width of the tape contained in the machine. 110

What I claim is:—

1. In a machine of the character described, the combination of a container for a roll of gummed tape, a moistener, a retractor intermediate the said container and the said moistener and operating to draw the tape longitudinally thereof away from the moistener.

2. In a machine of the character described, the combination of a container for a roll of gummed tape, a moistener, a retractor intermediate the said container and the said moistener and operating to draw the tape longitudinally thereof away from the moistener, and tension control mechanism 120 acting on the tape at a point between the retractor and the container whereby the gummed tape on the side of the retractor toward the container is held immovable 125 against the action of the retractor. 130

3. The improved moistener comprising a container for a roll of gummed tape, moistening means and a retractor comprising a member movable bodily across the path of the gummed tape when it is drawn out and operating to draw the tape longitudinally thereof away from the moistener.
4. In a machine of the character described, the retractor which consists in a member normally resting on the tape at a point below the line occupied by the tape as it is being pulled out, said member being moved up across said line by the said tape when it is being pulled out, and itself moving the portion of said tape which is adjacent the retractor down out of said line when the tension on the tape is relaxed and thereby moving the end of the tape longitudinally.
5. In a machine of the character described, the retractor which consists in a movable member normally at rest at one side of the line occupied by the tape as it is being pulled out and a guide for the said member and across the line of movement of the tape, said movable member being moved by the tape across the line of movement of the tape as it is pulled out, and itself moving the portion of the tape which is adjacent the said movable member out of said line when the tension on the tape is relaxed and thereby moving the end of the tape longitudinally.
6. In a machine of the character described, the retractor which consists in a movable member resting on the said tape at a point below the line occupied by the tape as it is being pulled out, guides for the said movable member comprising a rod and sleeve, said movable member being lifted up by the said tape when it is being pulled out and itself moving downward by gravity to retract the tape when the tension on the tape is relaxed.
7. In a machine of the character described, the combination of a container for gummed tape, a moistener, a guide for the tape adjacent the moistener and a retractor movable across the path of the tape at a point between the container and the guide adjacent the moistener whereby the tape is drawn back lengthwise from the moistener.
8. In the improved stay strip moistening machine, the combination in series of a holder for a roll of gummed stay strip, a retractor, a guide, a moistener, a protecting member lying in contact with and covering up a portion of said moistener and located between said guide and said moistener, said retractor operating to withdraw stay strip from the moistener over said protecting member, and means for severing desired portions of said stay strip.

In testimony whereof I affix my signature, in presence of two witnesses.

CHARLES H. CROWELL.
